UNITED STATES PATENT OFFICE.

FRANK B. COMINS, OF NEWTON, AND JOSEPH ARMSTRONG, OF MALDEN, MASSACHUSETTS, ASSIGNORS TO AMERICAN MOISTENING COMPANY, OF BOSTON, MASSACHUSETTS, A CORPORATION OF MAINE.

HUMIDIFIER.

Application filed July 14, 1921. Serial No. 484,633.

To all whom it may concern:

Be it known that we, FRANK B. COMINS and JOSEPH ARMSTRONG, citizens of the United States, residing at Newton and 5 Malden, respectively, in the county of Middlesex and State of Massachusetts, have invented certain new and useful Improvements in Humidifiers, of which the following is a specification.

10 This invention provides an improved humidifier. It especially relates to humidifiers in which there is means to provide a spray of water and a fan to force circulation of air. Such apparatus is commonly supported from overhead in the upper part of a room and includes a sizable cylindrical casing set with vertical axis within which the spray is discharged, and at the top of which is the fan, turning on a vertical axis, and 15 driven by a water motor to which the fan is close coupled. Means must be provided to supply water to the motor and water to the spraying nozzle; there must also be means to take away the water from each.

20 The present invention provides for the practical elimination of these parts, as separate and obtrusive elements, by combining them with the hanger which supports the cylinder. Heretofore it has been the practice to 25 support humidifier casings from the ceiling by a suitable rod or strap hanger, and the water has been supplied by systems of piping, and, after passing through the motor, or jet, has been carried off by another system of piping. The present improvement 30 eliminates some expense, in that, aside from the cost of material, it saves expensive labor heretofore required to install the pipes and connections; decreases the net work of piping incidental to the humidifier system, makes the layout less complex, and makes it capable of being done more completely in the factory before installation; improves the 35 appearance when installed; decreases the weight carried by the ceiling or supports, and in general gives improved results.

According to the present invention the individual humidifiers are hung by tubing which may serve to conduct water from the supply pipe to the water motor inlet and from the motor outlet into the base pan of the humidifier, or through the base pan into the general return pipe of the system.

To this end the ordinary rod or strap hanger of a humidifier is replaced with 55 tubes, socketed in suitable fittings attached to the overhead beams or other supports, which tubes pass down along the sides of the humidifier and may, in fact, form part of its casing. Suitable connections are provided whereby water may flow into one of these hanger tubes near its top for use either in the nozzle or motor. Water that has passed through the motor and been conducted through the hanger to the base of the 60 humidifier casing may there be discharged to flush the pan, or, if desired, may continue to a level below the pan and be discharged into the drain pipe thereof, and thence directly into the return of the system, with a sort of ejector effect that helps 65 the drainage.

In the accompanying drawings, two preferred arrangements are pictured, but as the principles of the invention may be applied in other types, or combinations, the drawings are to be taken as merely illustrative. The patent is intended to cover, by suitable expression in the appended claims, whatever features of patentable novelty 70 exist in the invention disclosed.

In the drawings:

Figure 1 is an elevation of a humidifier embodying the invention;

Figure 2 is a side elevation of the same; 85

Figure 3 is a front elevation, showing a modification in the piping arrangement;

Figure 4 is a side elevation of the modification shown in Figure 3; and

Figure 5 is an enlarged view of a detail. 90

Referring to the drawings, the humidifier has, within its casing 11, a nozzle 10 for producing a conical spray above which is a water motor 12 adapted to drive a fan 13 to force air through the casing and incidentally 95 through the conical spray within said casing. The casing 11 has tubular vertical supports comprising pipes whose upper portions 14 are screwed into sockets 15 attached to the overhead beams of the room. These 100 pipes support the humidifier, also form part of the water supply system.

In Figures 1 and 2 the water supply system is of the multiple type in that the water supply for the nozzle 10 is separate from 105 the water supply for the motor. The nozzle

supply in this arrangement forms no part of the invention, as it comes to the humidifier in suitable small pipes, 16, connected thereto in the customary manner, having no relation to the hanger pipes. The motor supply however, instead of being piped directly to the motor, enters one of the hanger pipes near its upper end by a T joint coupling 17. Below this connection and forming a part of the hanger pipe is a filter 18, and at some convenient place, either in the supply pipe 19 or between the T coupling and the filter, as illustrated, a valve 20 may be placed whereby the water through the motor can be controlled. Between the filter and the top of the humidifier casing a clamp connection 21 on the hanger pipe permits the attachment thereto of a short supply pipe 22 which constitutes the motor inlet. Below the clamp connection a plug joint or union 23 may be inserted in the hanger pipe, to prevent the water from descending further through the leg of the hanger pipe. The outlet pipe 24 from the motor is connected by a similar clamp connection 21' to the other hanger pipe. The water passes down through the portion 26 of this hanger pipe and, in the embodiment shown in Figures 1 and 2, passes therein through the base or pan 28 of the humidifier casing, below which it is conducted into the return pipe 30 to flow therethrough across the end of the discharge 32 from the pan. In this arrangement the motor discharge acts as a straight line flush to keep the return pipe well cleaned, and also acts with a sort of ejector effect to move any accumulation in the pan.

In Figures 3 and 4 a unit supply system is illustrated wherein the water for both the nozzle and the motor is brought to the humidifier in a single supply pipe 40 and passes through a valve 42 and filter 44 before being separated. The branch 46 leading to the nozzle 10 leads through a diaphragm valve 48 by which the discharge from the nozzle is automatically controlled, by suitable means which are well known and need not here be described.

In the arrangement of Figures 1 and 2 there may be individual diaphragm valves as here or a single diaphragm valve may control a whole battery of nozzles; but in the unit supply system of Figures 3 and 4 the water for each nozzle is supplied from the same source as the water for its motor, and the desire to keep the motor continuously running, with only occasional operation of the spray, is met by putting a diaphragm valve into each branch leading to a nozzle.

The other branch 50 leading from the supply pipe below the filter is shown connected directly to the motor, from which the water may be discharged through two

separate outlet pipes 52 and 54, each of which leads to one of the hanger pipes. The connection between these outlet pipes and the hanger pipes may be the same kind of clamps connected as heretofore described, or by any other suitable type 56. Another method of discharge is shown in Figures 3, 4 and 5 wherein the lower ends 58 of the hanger pipes, are provided with perforated nuts 60 through the perforations 62 of which the water may discharge into the base pan 28 of the humidifier casing. A stem 64 provided on these perforated nuts extends downward through the bottom of the casing to permit another nut 66 to be threaded on the stem so as to hold a support 68 for the humidifier base. The water thus discharged into the pan of the casing continually washes out its bottom and passes off through the regular return pipe 30 of the system.

The features of conducting the discharge from the motor into both hanger pipes, and thence through openings therein into the pan of the humidifier are made the subject matter of our divisional application, Serial No. 696,332 filed March 1, 1924.

The tubular hangers thus both support the humidifier and conduct its water; with appearance greatly improved, and with economy of construction.

We claim:

1. In a humidifier, the combination with a water motor of a tubular hanger constituting both a support for the humidifier and a conduit for water passing through said motor.

2. In a humidifier the combination with a water motor and a spraying nozzle of a tubular hanger adapted to support the humidifier and to serve as a conduit for the water passing through the motor and the nozzle.

3. In a humidifier the combination with a water motor of a pair of tubular hangers adapted to support the humidifier and to serve as conduits for the water passing through the motor; said hangers affording supply passage to the motor and discharge passage therefrom.

4. In a humidifier the combination with a water motor of a pair of tubular hangers adapted to support the humidifier and to serve as conduits for the water passing through the motor; one of said hangers affording supply passage to the motor and the other of them being connected with and conducting its discharge water into the return piping from the humidifier.

5. A humidifier having a casing, a spraying nozzle in it, a pan under it with a discharge outlet, a fan and a water motor; combined with a pair of pipes passing through said pan and adapted to support the humidifier, one of which pipes has a por-

tion constituting a water supply passage and one of which pipes has a portion constituting a motor-water discharge passage, there being a connection at the bottom of the 5 last said pipe to the discharge outlet of the pan.

6. A humidifier comprising a casing, a fan and a water motor close-coupled at the upper end thereof, a pair of pipes constituting hangers for the humidifier and conduits for the water passing through the 10 motor, and a second pair of pipes each of which is connected to one of the first said pair and to the motor, whereby the motor 15 and fan are supported in operative position,

and through which the motor-water may be conducted.

7. In a humidifier the combination with a water motor of a hanger adapted to support the humidifier and to constitute a portion of the water supply passage to the 20 motor, the said portion comprising a connection with a water supply pipe, a valve controlling the supply to the motor, a filter, and a connection leading to the motor. 25

Signed at Boston, Massachusetts, this eleventh day of July, 1921.

FRANK B. COMINS.
JOSEPH ARMSTRONG.
